ATTORNEY.

UNITED STATES PATENT OFFICE.

JAMES H. BRENNAN, OF SHULLSBURG, WISCONSIN.

TRACE-BEARER.

SPECIFICATION forming part of Letters Patent No. 392,309, dated November 6, 1888.

Application filed June 15, 1886. Serial No. 277,260. (No model.)

To all whom it may concern:

Be it known that I, JAMES H. BRENNAN, of Shullsburg, in the county of Lafayette and State of Wisconsin, have invented a new and useful Improvement in Trace-Bearers, of which the following is a specification.

My invention is an improvement in trace-bearers, and seeks to provide certain novel constructions and combinations of parts, where-
10 to by the lower end of the round trace-bearing loop is strengthened and re-enforced, and its connection with the supporting strap or skirt is rendered more secure.

The invention consists in certain novel constructions and combinations of parts, as will 15 be hereinafter described and claimed.

In the drawings, Figure 1 is a perspective view of a trace-bearer provided with my improvement. Fig. 2 is a detail view of the re- 20 enforcing plate; and Fig. 3 is a section on line *x x*, Fig. 1.

The strap A forms the support, and may be the skirt-strap of a harness-saddle. To the support I fix the upper end of the loop-strap 25 B, which strap is preferably rounded at its looped portion, as shown. The re-enforcing plate C fits and is secured within the lower portion of the bearer-loop and receives in use the wear of the trace, as will be readily seen, 30 the main portion of the plate being properly curved, as shown. This plate C, as shown, is formed with a main or curved portion, C', provided at its upper end with a clamp lug or lugs, C², preferably projected from its oppo- 35 site sides, which lugs may be bent over the loop-strap, as shown in Fig. 1, to secure the strap to the plate, the plate being grooved at C³ to receive such strap. The base portion or extension C⁴, at the lower end of the plate C, 40 is perforated for the passage of the rivet D, which secures the lower end of the bearer-loop to the skirt or support A, and also secures the re-enforcing plate and the billet-strap E. Preferably the portion C⁴ is grooved or recessed at

C⁵ to receive the end of the bearer-strap and 45 of the billet E, and slotted at C⁶ for stitches extending between said straps and the skirt, in order to hold the straps down tightly within the recess C⁵.

It will be seen that the re-enforce, in addition to being useful in new work, may also be employed to great advantage in repairing work.

The plate may be made of malleable metal, and be nickel-plated, japanned, or otherwise suitably ornamented.

Having thus described my invention, what I claim as new, and desire to secure by Letters Patent, is—

1. The improved re-enforce plate for trace-bearers, consisting of the main or curved portion provided at its upper end with the clamp lug or lugs free at one end, whereby they may be bent around the loop strap, and the base portion or extension projected from the lower end of the main portion and grooved or recessed in its outer side to receive the end of the bearer-strap and of the billet, substantially as set forth.

2. As an improved article of manufacture, a re-enforce plate for round trace-bearers, consisting of the base portion C⁴ and the main portion C, extended at its lower end from the extreme upper end of the base portion, such main portion being curved longitudinally and having in its outer side a rounded groove fitted to receive the round trace-bearer strap, substantially as set forth.

3. The improved re-enforcing plate for round bearer-straps, consisting of the base portion C⁴, recessed in its outer side and provided with slots 80 C⁶ C⁷, and the main portion C, having a longitudinal rounded groove, C⁸, and provided at its upper end with lugs C⁹, such portion C being curved, substantially as set forth.

JAMES H. BRENNAN.
